(57) **CLAIM**

The ornamental design for a throwable ball, as shown and described.

DESCRIPTION

FIG. 1 is a front and left perspective view of the throwable ball showing our new design;

FIG. 2 is a left side view thereof;

FIG. 3 is a front view thereof; the rear view being the same the same except for the area occupied by the raised lettering shown in broken lines;

FIG. 4 is a rear and right perspective view thereof;

FIG. 5 is a right side view thereof; and,

FIG. 6 is a top view thereof.

The broken lines are included for the purpose of illustrating portions of the throwable ball that form no part of the claimed design.
